UNITED STATES PATENT OFFICE.

JAMES M. EIFFE, OF FULTONVILLE, NEW YORK, ASSIGNOR TO WHITE MOP WRINGER COMPANY, OF FULTONVILLE, NEW YORK, A CORPORATION OF NEW YORK.

DESIGN FOR A PAIL.

Application filed April 2, 1927. Serial No. 21,435. Term of patent 14 years.

To all whom it may concern:

Be it known that I, JAMES M. EIFFE, a citizen of the United States, residing at Fultonville, in the county of Montgomery and State of New York, have invented a new, original, and ornamental Design for Pails, of which the following is a specification, reference being made to the accompanying drawing, forming part thereof.

Figure 1 is a plan view of the pail.

Figure 2 is a perspective view of the pail showing my new design.

I claim:

The ornamental design for a pail as shown.

JAMES M. EIFFE.
